CLAIM

The ornamental design for a support arm as shown and described.

DESCRIPTION

FIG. 1 is a front, right, top perspective view of a support arm showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, right bottom perspective view thereof;

FIG. 9 is a perspective view of the support arm shown in an alternate configuration with broken line environment; and, FIG. 10 is a perspective view of the support arm in a state of use with broken line environment.

The portions shown in dashed lines form no part of the claimed design.

1 Claim, 10 Drawing Sheets
